(57) **CLAIM**

I claim the ornamental design for a combined curved card holder with tray clip, as shown and described.

DESCRIPTION

FIG. 1 is a perspective view of a combined curved card holder with tray clip, showing my new design;

FIG. 2 is a left side view of FIG. 1;

FIG. 3 is a right side view of FIG. 1;

FIG. 4 is a front view of FIG. 1;

FIG. 5 is a back view of FIG. 1;

FIG. 6 is a bottom view of FIG. 1; and,

FIG. 7 is a top view of FIG. 1.

1 Claim, 2 Drawing Sheets

FIG. 1

FIG. 2

FIG. 3

FIG. 4

FIG. 5

FIG. 6

FIG. 7
